Inventor:

UNITED STATES PATENT OFFICE.

BARTLETT J. PALMER, OF DAVENPORT, IOWA.

MOUNTING FOR BONES.

1,073,703.

Specification of Letters Patent. Patented Sept. 23, 1913.

Application filed November 29, 1912. Serial No. 734,142.

To all whom it may concern:

Be it known that I, BARTLETT J. PALMER, a citizen of the United States, residing at Davenport, in the county of Scott and State of Iowa, have invented certain new and useful Improvements in Mountings for Bones, of which the following is a specification.

This invention relates to an improvement in a mounting for bones of a body, and more particularly to a mounting of this character which may be used in the study of osteopathy and chiropractic.

The theory of chiropractic is that all diseases are caused by displacement of the vertebrae causing them to press upon the large nerve branches which pass out from the spinal cord orifices between the vertebrae, which pressure upon the nerve branches prevents the proper circulation of the nerve forces and thus causes the organs to which these branches lead to become diseased, and the primary object of the present invention is the provision of a simple and efficient mounting for vertebral sections of such a character that the vertebral sections may be shifted relatively to each other so as to illustrate to the student, the results caused by such shifting or displacement of the vertebral sections.

Other objects of the invention will be apparent from the detailed description hereinafter, when read in connection with the accompanying drawings forming a part hereof, wherein a convenient embodiment of the invention is illustrated, and wherein like characters of reference refer to similar parts in the several views.

In the drawings: Figure 1 is a front elevation of the improved mounting. Fig. 2 is a plan view.

Referring now more particularly to the drawings A A designate a pair of supporting plates or members, the adjacent edges of which are slightly separated, and the end portions of which are connected by parallel links B B, the ends of which are pivotally connected by suitable screws or other fastening means b to the supporting plates A A.

C C designate two superposed vertebral sections one of which is rigidly secured to each of the supporting plates A A. In the particular embodiment of the invention illustrated in the drawings, each of the sections C C comprise one half of a complete

vertebra, such vertebra being cut vertically through the body and spinous process thereof to produce one of the sections C. In securing the sections C C to the supporting members A A, each of said sections is secured with the flat side, produced in cutting the same, directly against the outer face of the supporting section, so that when the two sections have been secured to the supporting plates in their proper relation, a side view of the vertebrae is presented.

Interposed between the adjacent ends of the bodies of the sections C C is an intervertebral pad D which is conveniently formed of felt, soft rubber, or like material. Positioned between the orifice formed between the transverse spinous processes is a short piece of rubber or other elastic tubing E which is intended to represent one of the nerve branches which pass out from the spinal cord through orifices in the vertebrae.

When the supporting members A A are in their normal or proper position, the sections C C of the vertebrae carried thereby will also be in their normal positions, and the tube E will not be compressed. Owing to the link connections between the supporting members A A it will be seen that such members can be shifted laterally relatively to each other, and when the members are so shifted the vertebral sections will also be shifted relatively to each other and portions of the sections will be caused to engage the tube E and partially compress the same, thus vividly illustrating to the student the results which are produced by a displacement of one of the vertebral sections relatively to the other. The displacement of the vertebral sections C C in this manner also shows the results of a displacement of one of the sections of the vertebra of a human body relatively to the other upon the intervertebral pad between the sections of the vertebrae.

The connection between the members A A is such that such members, when shifted relatively to each other, will remain in their shifted position until they are shifted relatively to each other to restore the same to their normal positions, so that ample opportunity is given to enable proper observation of the parts when in their normal positions.

While in the form of the invention illustrated in the accompanying drawings each of the sections C C is illustrated as comprising but one-half of a complete vertebra,

it is obvious that complete vertebral sections might, if desired, be mounted upon the supporting members, and while but two sections of the vertebrae are illustrated in the 5 accompanying drawings, it will be obvious that any number of sections or any portion of a spine may be employed.

While a convenient embodiment of the invention is illustrated in the accompanying 10 drawings, it will be understood that many changes may be made to the particular form and construction therein shown without departing from the spirit and scope of the invention as defined in the appended 15 claims.

I claim:

1. A mounting for bones of the character described comprising a pair of adjacent supporting members, a pair of superposed vertebral sections, one of which is rigidly secured to each of said supporting members, and means for connecting the supporting members whereby one of said members may be moved laterally relatively to the other of 20 said members.

2. A mounting for bones of the character described comprising a pair of supporting members, a pair of superposed vertebral sections, one of said sections being rigidly secured to each of said supporting members, pads between the adjacent bodies of said vertebral sections, and means for connecting the supporting members whereby one of said members may be moved laterally relatively to the 30 other of said members.

3. A mounting for bones of the character described comprising a pair of supporting members, a pair of superposed vertebral sections, one of which is rigidly secured to each 40 of said supporting members, an elastic tubular member positioned in the orifice formed between the vertebral sections, and connections between said supporting members whereby one of said supporting members 45 may be moved laterally relatively to the other of said supporting members.

4. A mounting for bones of the character described comprising a pair of supporting members, a pair of superposed vertebral sections, one of which is rigidly secured to each 50 of said supporting members, a pad between the adjacent portions of the bodies of said

vertebral sections, an elastic tubular member positioned in the orifice formed between the vertebral sections, and means for connecting the supporting members whereby one of said members may be moved laterally relatively to the other of said members.

5. A mounting for bones of the character described comprising a pair of supporting members, a pair of superposed vertebral sections, one of which is rigidly secured to each of said supporting members, and a pair of parallel links having their ends pivotally connected to said supporting members whereby one of said members may be moved laterally relatively to the other of said members.

6. A mounting for bones of the character described comprising a pair of supporting members, a pair of superposed vertebral sections, one of which is rigidly secured to each of said supporting members, a pad between the adjacent portions of the bodies of said vertebral sections, and a pair of parallel links having their ends pivotally connected to said supporting members.

7. A mounting for bones of the character described comprising a pair of supporting members, a pair of superposed vertebral sections, one of which is rigidly secured to each of said supporting members, an elastic tubular member positioned in the orifice between said vertebral sections, and a pair of parallel links having their ends pivotally connected to said supporting members.

8. A mounting for bones of the character described comprising a pair of supporting members, a pair of vertebral sections, one of which is rigidly secured to each of said supporting members, a pad between the adjacent portions of the bodies of said vertebral sections, an elastic tubular member positioned in the orifice formed between the two vertebral sections, and a pair of parallel links having their ends pivotally connected to said supporting members.

In testimony whereof I affix my signature in presence of two witnesses.

BARTLETT J. PALMER.
